(57) **CLAIM**

We claim the ornamental design for a burner controller cover, as shown and described.

DESCRIPTION

FIG. 1 illustrates a top front and right side perspective view of a burner controller cover such as may be used in association with a controller of a fuel oil burner according to one exemplary aspect of the present invention.

FIG. 2 illustrates a top front and right side perspective view of the burner controller cover of FIG. 1.

FIG. 3 illustrates a top plan view of the burner controller cover of FIG. 1.

FIG. 4 illustrates a front side elevation view of the burner controller cover of FIG. 1.

FIG. 5 illustrates a rear side elevation view of the burner controller cover of FIG. 1.

FIG. 6 illustrates a right side elevation view of the burner controller cover of FIG. 1; and,

FIG. 7 illustrates a left side elevation view of the burner controller cover of FIG. 1.

The broken lines shown in FIG. 1 are for illustrative purposes only and form no part of the claimed design.
